UNITED STATES PATENT OFFICE.

WALTER P. GRATH, OF ST. LOUIS, MISSOURI.

FURNACE.

SPECIFICATION forming part of Letters Patent No. 636,037, dated October 31, 1899.

Application filed November 23, 1898. Serial No. 697,282. (No model.)

To all whom it may concern:

Be it known that I, WALTER P. GRATH, a citizen of the United States of America, and a resident of the city of St. Louis, in the State 5 of Missouri, have invented a certain new and useful Furnace, of which the following is a specification.

My invention relates to furnaces, and has for its principal objects to utilize coal-slack 10 as fuel and to avoid the generation of dense clouds of smoke.

To these ends my invention consists in providing the combustion-chamber of the furnace with shelves or platforms for supporting the 15 fresh slack and in so arranging the draft-flues that such slack will be thoroughly coked before it is applied to the fire-grate.

In the accompanying drawings, which form part of this specification, Figure 1 is a front 20 elevation of a furnace embodying my invention. Fig. 2 is a cross-section thereof on the line 2 2 of Fig. 3, and Fig. 3 is a horizontal section on the planes indicated by the line 3 3 of Fig. 1.

Like symbols refer to like parts wherever 25 they occur.

The outer walls 1 and roof of my furnace are built in any usual way of brick or other suitable material to inclose the grate 2 and 30 the combustion-chamber. From one or both of the side walls shelves 3 extend horizontally to form brackets or platforms, which are located a convenient distance above the grate. The inner edges of these shelves or platforms 35 are preferably supported on walls 4, having openings therein, or on columns arranged to leave spaces between them. Such columns or walls thus constitute a fire-box or convenient means for confining the fuel, but allow 40 the products of combustion to enter and circulate freely in the spaces or flues under the shelves, which spaces are in effect lateral extensions of the combustion-chamber. As the shelves are imperforate, the spaces in the 45 combustion-chamber above the shelves are cut off from the supply of air and constitute coking-chambers, which are continuous with the combustion-chamber. The outer rear wall is protected by a fire-wall 5, having an 50 opening 6 in its upper middle portion and a

smaller opening 7 below each side shelf, communicating with the flue or extension of the combustion-chamber below said shelf.

The front of my furnace is built with openings therein communicating, respectively, 55 with the fire-box, each of the coking-chambers at the sides thereof, the ash-pit below the grate, and each of the side flues below the coking-chambers, and a door is provided for each of these openings. The outer rear 60 wall has a single outlet-opening 8 for the hot products of combustion.

The operation of my device is initiated by building a fire of any suitable fuel upon the grate in the fire-box, and the slack to be used 65 for fuel is piled on the two shelves or platforms at the sides. The air necessary for combustion is supplied through the ash-pit and grate, and the main volume of the products of combustion pass out through the opening in the fire-wall, whence they pass through the opening in the outer rear wall into the kiln, boiler, or other place. A portion of the products of combustion, however, pass 70 through the opening in the sides of the fire-box into the extension or flues below the respective coking-chambers, and thence through the openings in the inner rear wall into the rear flue, and thence out through the opening 75 80 in the outer rear wall along with the main volume, which had taken the more direct course. By this arrangement the slack in the coking-chambers is not only exposed above to the direct heat in the fire-box, but as the shelves or platforms which constitute 85 the bottom of the coking-chambers are the tops of the side flues or extensions of the combustion-chamber as well, such slack is exposed below to the heat in the flues or chamber. Thus all portions of the slack are sufficiently heated to become thoroughly coked, 90 and the hot gases generated therefrom are driven off into the draft of air coming up through the grate and are consumed. When new fuel is required for the fire-box, the coke 95 thus formed is raked off the side shelves in one or more large masses onto the grate and a supply of fresh slack is shoveled into the coking-chambers.

While the construction represented in the 100

drawings is the best form of my device, my invention admits of considerable modification. For instance, instead of having one fire-box between two shelves there may be only one shelf extending from the wall or there may be one central platform between two fire-boxes, and in either case satisfactory results are obtained by providing openings in the side or sides of the fire-box for the free radiation of heat and circulation of products of combustion without providing any special outlet therefrom. So, also, where no inner walls are used for limiting the fuel or where the openings therein are sufficiently large no special outlet-opening need be made under the shelves or platforms.

My furnace is specially designed for burning coal-slack and is applicable for heating kilns, boilers, and other furnace uses. Its most important advantages are that it thoroughly cokes all the slack before burning the same, whereby the maximum heating value of the fuel is obtained, smoking is avoided, and the fire easily regulated.

Another important advantage is that part of the gases generated in the coking-chambers and escaping therefrom are carried along in the draft for a considerable distance before ignition, whereby the heat may be distributed more evenly through the kiln.

What I claim is—

1. A furnace comprising outer walls inclosing a grate and a combustion-chamber and having a raised imperforate platform arranged under the roof of the combustion-chamber and extending horizontally from a wall thereof so that a mass thereon may be pushed off onto said grate, the space beneath said platform being open to the products of combustion, and the space above said platform being continuous with the combustion-

chamber and cut off from the supply of air, substantially as and for the purpose set forth.

2. A furnace comprising outer walls, a fire-box therein having a separate wall with openings therein, and a shelf extending from said fire-box wall to the outer wall, said furnace being provided with a flue for the main draft from the combustion-chamber and a secondary outlet-flue communicating with the chamber beneath said shelf, substantially as and for the purpose set forth. 45

3. A furnace comprising outer walls, a fire-box therein having separate side walls provided with outlet-openings, a platform on each side of the fire-box extending from the top of the fire-box wall to the outer wall, said furnace being provided with a main-draft flue opening into the rear end of the combustion-chamber and secondary-draft flues communicating with the space beneath the side platforms, substantially as and for the purpose set forth. 55

4. A furnace comprising outer walls, a fire-box therein having a fire-wall at the rear thereof provided with the main outlet-opening for the products of combustion, and having separate side walls provided with secondary outlet-openings, and platforms extending from the side walls of the fire-box to the outer walls, the chambers below said platforms communicating with the space back of the fire-wall, the outlet-opening for the products of combustion being located in the rear wall, substantially as and for the purpose set forth. 60 70 75

Signed at St. Louis, Missouri, this 19th day of November, 1898.

WALTER P. GRATII.
